UNITED STATES PATENT OFFICE.

HALWARD G. WESTMORE, OF MILWAUKEE, WISCONSIN, ASSIGNOR TO A. O. SMITH CORPORATION, OF MILWAUKEE, WISCONSIN, A CORPORATION OF NEW YORK.

PORTABLE RIVETING HAMMER.

Application filed March 29, 1920. Serial No. 369,472.

To all whom it may concern:

Be it known that I, HALWARD G. WESTMORE, a citizen of the United States, and resident of the city of Milwaukee, county of Milwaukee, and State of Wisconsin, have invented a certain new and useful Improvement in Portable Riveting Hammers; and I do declare the following to be a full, clear, and exact description thereof, such as will 10 enable persons skilled in the art to which the invention pertains to make and use the same, reference being had to the accompanying drawings, as showing one construction in which my invention has been embodied.

15 The invention relates to power actuated portable riveting hammers or devices.

The invention resides in a construction embodying a casing which supports the anvil in a position of longitudinal adjustment 20 with reference to the hammer. In the form illustrated the invention has been constructed so as to be operated by compressed air. The casing referred to also supports the riveting hammer and the cylinder in which 25 the hammer piston works.

The provision for longitudinal adjustment of the anvil in its supporting casing enables the device to be quickly adapted to meet variations in the work, without in any 30 way involving the necessity of modifying the stroke of the hammer to meet such contingencies. The invention further comprises means for retracting the hammer to its rearmost position immediately upon relaxation of the air pressure, so that the device may be changed from one position to another without interference or obstruction 35 by the hammer moving from its normal retracted position.

40 The invention also comprises means for suspending the riveting device for operation either in vertical or horizontal position, with provision for immediate change of the device from one position to the other.

45 The novel features of the invention will be pointed out in the appended claims.

In the drawings accompanying this specification,

Figure 1 is a view in elevation showing 50 my improved riveting hammer in position for spreading vertically placed rivets, this view showing also, in dotted lines, the relative arrangement of the riveting hammer

when shifted into position for spreading horizontally extending rivets.

Fig. 2 is a sectional view through the riveting device on the line 2—2, looking in the direction of the arrow, but omitting the anvil and the cylinder with its hammer.

The riveting hammer embodying the present invention has been particularly designed for riveting together the side bars and cross bars, as well as other connecting members, of an automobile or other vehicle frame, the parts of such frame being formed from sheet metal plates, in a manner well known. In operation, the assemblage of parts constituting the automobile frame will be supported at a suitable level, and the rivets designed to unite such parts will be placed in the several openings provided in the frame parts for the reception thereof. The riveting device will be suspended from an overhead track so as to be in proximity to the assemblage of frame parts, and may be quickly moved into the several positions with respect to the frame where the riveting operations are to be performed.

The casing A is formed of a casting and is provided with two parallel bores a and a^1 , extending longitudinally thereof. The anvil B is provided with a threaded shank b which is passed into the bore a and adjusted with reference to the stroke of the hammer and to the work to be performed, by means of the jam nuts b^1 , bearing against the ends of the casing. By moving the jam nuts, on the threaded shank b , the anvil may be gradually adjusted exactly and with precision to the position necessary to effect the most satisfactory results. The face b^2 of the anvil is formed upon a horn b^3 extending at a right angle to the shank b , and is positioned axially with reference to the riveting hammer. By this arrangement the impact of the blow of the hammer upon the anvil is transmitted in a direct manner to the casing. The anvil is positively retained against longitudinal movement in the position to which it has been adjusted, so that any change of the position thereof by the blows of the hammer is prevented.

The cylinder for the riveting hammer C is seated within the bore a^1 of the casing and is clamped therein by binding bolts a^2 passing transversely through the casing and

serving to close the radial slot a^3 extending from the bore a^1 and thus finally hold the said cylinder in its operative position with respect to the casing and the horn of the 5 anvil. The compressed air for operating the hammer C through the usual piston is admitted to the cylinder by means of the duct c, leading from a source of supply.

In order to render the riveting device 10 readily movable from one position to another, it is necessary to bring about the immediate retraction of the hammer upon completion of each riveting operation so that there will be neither delay nor interference in effecting the movement. This result I achieve by connecting a retracting spring to the riveting hammer, which serves to withdraw the said hammer to its rear-most position immediately upon the relaxation 20 of the operating pressure. In the form illustrated this retracting device is shown as a band D which encircles the riveting hammer at a point outside of the casing A, and is clamped upon the said rod by means 25 of a bolt d^1 passing through the extended parallel end portions d^{10} of the loop D. To the said extended end portions of the loop D, tension springs d^2 are connected, the other ends of such springs being attached to 30 a post d^3 extending from the rear end of the casing. In the construction shown the said springs d^2 pass through openings d^4 formed in the connecting horizontal webs a^5 of the casing. In operation, the movement 35 of the hammer C to effect the spreading of the rivet and unite the parts, when the air is first admitted will overcome the tension and distend the said springs, without in any way affecting the efficiency of the 40 riveting mechanism. As hereinbefore indicated, the tension of the springs will serve to retract and hold the riveting hammer in its inoperative position when the riveting operation has been completed and the pressure 45 relaxed.

In order to enable the riveting device to be quickly shifted from vertical to horizontal position, and vice versa, to adapt it to upset rivets placed in either position, I 50 provide a bail E connected in fixed relation at one end to the rear of the casing, in the present construction to the post d^3 , and at the other end to a lug a^4 projecting from one side of the casing, viewing Fig. 1, 55 in which it will be seen that the said bail extends mainly in the longitudinal direction of the casing. The said bail E is bent at e and e^1 to form holding notches in which a ring e^2 , encircling the bail, may rest. The 60 holding notches e and e^1 are formed in the bail at points with due regard to the center of gravity and will evenly balance the riveting device in either of its positions, and will form supporting bearings upon which 65 the riveting device may be easily rocked

when desired by the operator to correctly position the same with reference to the work. The chain indicated in Fig. 1 leads from the ring e^2 to the overhead track from which the riveting device is suspended. In 70 traversing the riveting device along the assembled frame the said device may be instantly shifted from vertical to horizontal position, and vice versa, to accommodate it to the exigencies of the arrangement of the 75 rivets in the frame.

For convenient manipulation, the riveting device may be provided with a handle F. It will be observed that the anvil B is capable of radial adjustment so as to exactly 80 position the face b^2 thereof with relation to the riveting hammer.

Having thus described my invention, what I claim and desire to secure by Letters Patent of the United States, is:

1. A portable riveting device comprising a casing, a hammer and an anvil carried thereby, the latter being longitudinally adjustable with relation to the stroke of the hammer, means for supporting the device 90 in either vertical or horizontal position, connections for operating the hammer, and means for retracting the hammer to its inoperative position upon completion of the riveting operation.

2. A portable riveting device comprising a movable hammer and an anvil, a casing by which the said parts are carried, a fixed bail attached to and extending longitudinally of the riveting device, to suspend the 100 device in balanced horizontal or vertical position during the riveting operation.

3. A portable riveting device comprising a casing supporting a movable hammer and an anvil, a bail in fixed relation to the casing, means for suspending the riveting device in either vertical or horizontal position, such suspending means engaging the bail at points in line with the center of gravity of the device in either of said positions, the 110 bail permitting free movement of the said suspending means from one point to the other.

4. A portable riveting device comprising a casing, a movable hammer and an anvil 115 carried thereby, a bail for supporting the device in either vertical or horizontal position, and means for retracting the hammer to inoperative position upon completion of the riveting operation, such retracting 120 means being constituted of a tension spring connection between the casing and the hammer.

5. A portable riveting device comprising a casing, a hammer movable therein, and 125 an anvil adjustable to and from the hammer and in a plane parallel thereto, the shank of the anvil being seated in the casing and held in adjusted position by jam nuts bearing upon opposite ends of the casing.

6. A portable riveting device comprising a casing, a hammer movable therein, an anvil carried by the casing and held against movement under the blows of the hammer, and a fixed bail attached to the casing for suspending the device in a state of balance in its several riveting positions.

In testimony whereof, I have signed my name at Milwaukee, this 24th day of March, 1920.

H. G. WESTMORE.
